NEWSPAPER DISPLAY BAG

Jack W. Serdahely, Milwaukee, Wis.

Application November 25, 1938, Serial No. 242,368

1 Claim. (Cl. 206—44)

This invention relates to bags or cases especially useful by newsboys engaged in the sale of newspapers and the like, and has for the primary object the provision of a device of this character which will be durable, compact, easy to place papers in and remove therefrom and will efficiently display a paper so that the headlines may be conveniently read and will protect the papers from weather elements and the one on display.

With these and other objects in view, the invention consists in certain novel features of construction, combination and arrangement of parts to be hereinafter more fully described and claimed.

For a complete understanding of my invention, reference is to be had to the following description and accompanying drawing, in which

Figure 1 is a perspective view illustrating a newspaper display case or bag constructed in accordance with my invention.

Figure 2 is a transverse sectional view taken on the line 2—2 of Figure 1.

Figure 3 is a plan view illustrating the blank from which the case or bag is constructed.

Referring in detail to the drawing, the numeral 5 indicates a blank from which the case or bag is constructed and consists of a sheet of waterproof material foldable on the dotted lines, as shown in Figure 3, to form opposed front and rear walls 6 and 7, flaps 8 and 9 on said walls, the front wall 6 having a comparatively large opening 10 therein. The sheet of material is further folded to form a top wall 11 and a tuck portion 12 disposed outwardly of the front wall. The front wall 6 besides having the flaps 8 also has a flap 13. The flaps 9 of the rear wall 7 are folded upon themselves to present flaps 14 which also overlie the front wall 5. The flaps 14, 13 and tuck portion 12 coact in presenting a frame-like construction to receive therein a sheet of transparent material 15 acting as a display window and a closure for the opening 10. The sheet of transparent material 15 is stitched or otherwise secured onto the flaps 13, 14 and the tuck portion 12. The sheet of material 15 besides forming a closure for the opening 10 provides a chamber between itself and the front wall 6 to receive a newspaper by way of the opening 10 so that the major portion of the newspaper will be displayed in clear view whereby a person may readily read the headlines thereof. It is to be understood that the newspaper is inserted in the chamber from inside of the bag or case by way of the opening 10.

The top wall 11 has formed thereon tongues or flaps 16 and these flaps are adapted to be brought into engagement with the flaps 8 and 9 when the latter are brought into overlapping relation thereby assembling the front and rear

walls in spaced parallel relation. The flaps 8, 9 and 16 are stitched or otherwise secured together thereby completing the bag or receptacle which has its lower side or bottom fully open to permit newspapers to be readily placed therein and removed.

In use, the bag or case is to be carried under the arm of a newsboy and by placing the hand over the bottom the newspapers will be prevented from falling out of the bag or case and when it is desired to remove a paper on the sale thereof, the newsboy with the other hand readily extracts the newspaper from the bottom of the bag or case.

A bag or case constructed in accordance with the foregoing will provide an efficient, durable and compact device which may be manufactured and sold at a comparatively low cost so that it may be readily purchased by newsboys and will permit the newsboys to display their newspaper in such a way that the headlines may be read and still the newspapers will be efficiently protected from weather elements and permit of the newspapers to be easily placed therein and removed singly on the sale thereof.

It is also believed that the simplicity and advantages of this invention will be perfectly apparent to those skilled in the art to which such device relates, and while I have herein set forth a satisfactory embodiment of the invention, it is to be understood that such changes therefrom as fairly fall within the scope of my claim may be resorted to when desired.

Having thus described my invention, what I claim is:

A device for carrying and displaying printed matter for sale comprising a waterproof case including connected front and rear walls and a top wall, said front wall having an opening, a tuck portion forming a continuation of the front and top walls and extending downwardly and outwardly from the front wall above said opening, a flap formed on the front wall and overlying a portion of the latter below said opening, flaps formed on the front and rear walls and arranged in overlapping relation to provide end walls for the case, said flaps of the rear wall being extended to overlie portions of the front wall and secured on the tuck portion and the first-named flap to coact therewith in providing a frame arranged about said opening, tabs formed on the top wall and secured to certain of said second-named flaps, and a sheet of transparent material secured on the frame and overlying the opening and coacting with the front wall and frame and forming a chamber on the exterior of the case and being in communication with the interior of said case by way of said opening.
